UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,163,869.

Specification of Letters Patent. Patented Dec. 14, 1915.

Application filed July 13, 1915. Serial No. 39,541.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to paper-feeding devices of typewriting machines, and especially to card-holders of the class illustrated in the patent to Allard, 769,811, of September 13, 1904, in which a stencil address card is inserted bottom edge first between the front of the platen and a pair of guiding rolls, the platen being rotated reversely to carry the card down until its bottom edge strikes the bottom of a pocket, which brings the device into position for writing the first line.

One of the principal objects of the present improvements is to enable the operator to feed the card positively in line-space direction by means of the platen itself, thus avoiding the necessity for using the complicated flat platen card attachments, which have been proposed by many inventors.

To carry out the present improvements, I arrange at each end of the usual revolvable platen, a gear, and in mesh with each gear, I arrange a pinion, and by means of a shaft, each pinion is connected to one of the card-guiding rolls. Each roll is thus positively driven, so that the card, although very brittle and therefore difficult to control, is positively clamped, being gripped between positively-driven rolls, instead of being driven by only one roll, namely, the platen, as in said patent. The roll shafts terminate at the rolls, leaving a clear open space between the rolls for writing on the card. The pressure of the spring which holds the rolls against the platen may be very strong, and the rolls may be made releasable by means of a handle projecting upwardly from the frame on which are carried the rolls and pinions, said frame being mounted to rock in the usual platen frame, being supported thereon by suitable gudgeons. The rolls are mounted in yielding fingers pending from said rock shaft, and carrying pockets at their lower ends to receive the cards. Either or both of these fingers may be adjustable along the rock shaft on which they are mounted; and to accommodate this adjust-

ment, each of the roll shafts is splined to its pinion, so that the shaft may permit adjustment of the feed roll along the platen while the pinion remains in mesh with its gear, in each instance. 60

Other features and advantages will hereinafter appear.

In the accompanying drawings, Figure 1 is a front elevation view of a portion of an Underwood typewriting machine, with the present invention applied thereto. Fig. 2 is a fragmentary part sectional end elevation view showing a card-guiding roll and supporting finger. Fig. 3 is a similar view showing a portion of the line-spacing mechanism and the gearing between the platen and one of the card-guiding rolls. Fig. 4 is a fragmentary front perspective view.

A roller platen 5 has its axle 6 journaled in a platen frame 7, which may be shiftable up and down as usual in the carriage 8, to bring the platen to upper and lower case positions. Types 9 may be operated by the usual mechanism to strike against the front face of the platen. The platen is rotatable by hand wheels 10, and may also be rotated forwardly for line-spacing the work, by means of the usual line-spacing mechanism comprising an operating lever 11, to actuate a slide bar 12 carrying a pawl 13 for driving 70 the line-space ratchet wheel 14, fixed to the platen axle, to thereby rotate the platen. 75

In carrying out the present invention, card-guiding and feeding rolls 15 are caused to bear against the front face of the platen at or adjacent to the printing line, and at opposite sides of the printing point, said rolls arranged to be positively driven from the platen, and thereby positively feed the cards over the platen. Each of the rolls 95 15 is fixed to the inner end of a roll-driving shaft 16 on which is splined a pinion 17 running in mesh with a gear wheel 18, fixed to the platen at the end thereof, or otherwise connected to be driven by the platen. 100 These rolls may be made of hard material (e. g. steel) and knurled, to increase their efficiency.

A rock shaft 19 extending lengthwise of the platen above the printing line, is journaled in the ends of the platen frame, by means of gudgeons 20. The roll shafts 16 are supported adjacent their outer ends in arms 21 depending from the rock shaft, said arms arranged in pairs, or bifurcated, to 105 110

receive the pinions 17 and prevent them from being shifted lengthwise of the platen out of engagement with the gear wheels 18.

The inner ends of the shafts 16 are journaled in fingers 22, the upper ends of which are slidably mounted on the rock shaft 19, said fingers depending from the rock shaft and hooked at their lower ends to provide pockets 23 to receive the lower edge of the 10 card or work-piece. Each roll 15 with its associated guiding finger 22, is adjustable lengthwise of the platen, the splined connection between the shaft and its pinion permitting such adjustment. Set screws 25 are 15 provided to clamp said fingers in their adjusted positions.

The rolls 15 are held against the platen or the work-piece with a strong but yielding pressure, which may be provided by a spring 26. The fingers 22 have a non-rotatable connection with the shaft which permits the pressure of the spring to be transmitted through the shaft to the rolls. The latter are preferably made of steel or other hard 25 material, and are provided with knurled or roughened surfaces to grip the cards and prevent slipping. The cards are thus gripped between positively driven rolls, instead of being driven by the platen alone, 30 whereby slipping of the card is effectually prevented. The teeth of the intermeshing gears and pinions are made quite deep in order to retain them in driving relation when the rolls are moved outwardly sufficiently to accommodate a thick card 24.

A handle 27 permits the shaft 19 to be rocked to throw the guide fingers and rolls off the platen, thereby facilitating the insertion and removal of cards. A card 24 may 40 thus be quickly dropped into position between the platen and the guide fingers 22, the lower edge of the card resting in the pockets 23, with the card in position to be written upon. As the roll shafts 16 terminate at the guide fingers 22, an open or unobstructed space is provided between the guide fingers for a portion of the card to be written. The length of this space is adjustable to correspond with the dimensions 45 of the card to be written; said adjustment being effected by shifting either one or both of the guide fingers along the rock shaft.

Variations may be resorted to within the scope of the invention, and portions of the 55 improvements may be used without others.

Having thus described my invention, I claim:

1. The combination with a roller platen, of means for supporting and feeding a card 60 over the platen past the printing line while retaining the card in a substantially flat condition, said means comprising guides at opposite sides of the printing point for the edges of the card, a roll arranged to bear 65 against the edge of the card at or near the

printing line, and means forming a driving connection between said roll and platen to drive the roll from the platen.

2. The combination with a roller platen, of means for supporting and feeding a card 70 over the platen at the printing line while retaining the card in a substantially flat condition, said means comprising guides for the side edges of the card, a feed roll to bear against the outer face of the card at or adjacent to the printing line, a shaft on which said roll is mounted, and intermeshing gears connected respectively to the platen and shaft for positively driving the roll when the platen is rotated. 75

3. The combination with a roller platen, of means for supporting and feeding a card 80 over the platen at the printing line while retaining the card in a substantially flat condition, said means comprising guides for the side edges of the card; a feed roll to bear against the outer face of the card at or adjacent to the printing line, a shaft on which said roll is mounted, and intermeshing gears 85 connected respectively to the platen and shaft for positively driving the roll when the platen is rotated, said guides being relatively adjustable lengthwise of the platen to accommodate cards of different widths, 90 said shaft having a splined connection with its gear to permit adjustment of the roll and shaft along the platen. 95

4. The combination with a roller platen, of card-guiding and feeding means comprising feed rolls at opposite sides of the 100 printing point, to bear against the front face of the card at or near the printing line, and means forming positive driving connections between said rolls and the platen whereby said rolls are positively driven to 105 feed the card when the platen is rotated.

5. The combination with a roller platen, of card-guiding and feeding means comprising feed rolls at opposite sides of the 110 printing point to bear against the front face of the card at or near the printing line, and driving means for the rolls comprising a gear train between each of said rolls and the platen.

6. The combination with a roller platen, of card-feeding means comprising feed rolls to bear against the front face of the card at the printing line, said rolls located at opposite sides of the printing point, and an unobstructed space being provided between said rolls along the printing line, shafts carrying said rolls and extending therefrom along the face of the platen, gears connected to the platen, and pinions on said shafts in mesh with said gears to form positive driving connections from the platen to 115 said rolls. 120

7. The combination with a roller platen and a platen frame, of a rock shaft journaled in said frame and extending along the 125 130

5 platen, card-guiding fingers connected to said rock shaft at opposite sides of the printing point for supporting a card in a substantially flat condition over the printing point, card-feeding rolls mounted on said fingers and arranged to bear against the outer face of the card at the printing line, and means to rock said shaft to throw the rolls off the platen.

10 8. The combination with a roller platen and a platen frame, of a rock shaft journaled in said frame and extending along the platen, card-guiding fingers connected to said rock shaft at opposite sides of the printing point for supporting a card in a substantially flat condition over the printing point, card-feeding rolls mounted on said fingers and arranged to bear against the outer face of the card at the printing line, 20 means to rock said shaft to throw the rolls off the platen, and means to positively drive said rolls from the platen.

9. The combination with a roller platen and a platen frame, of a rock shaft journaled in said frame and extending along the platen, card-guiding fingers connected to said rock shaft at opposite sides of the printing point for supporting a card in a substantially flat condition over the printing point, card-feeding rolls mounted on said fingers and arranged to bear against the outer face of the card at the printing line, means to rock said shaft to throw the rolls off the platen, roll shafts carrying said 30 rolls and extending outwardly therefrom along the face of the platen, arms on said rock shaft in which the roll shafts are supported, gears connected with the platen, and pinions on the roll shafts to run in mesh with the gears and thereby positively drive the feed rolls when the platen is rotated.

10. The combination with a roller platen and a platen frame, of a rock shaft journaled in said frame and extending along the platen, card-guiding fingers connected to said rock shaft at opposite sides of the printing point for supporting a card in a substantially flat condition over the printing point, card-feeding rolls mounted on said 40 fingers and arranged to bear against the outer face of the card at the printing line, means to rock said shaft to throw the rolls off the platen, roll shafts carrying said rolls and extending outwardly therefrom along the face of the platen, arms on said rock shaft in which the roll shafts are supported, gears connected with the platen, and pinions on the roll shafts to run in mesh with the gears and thereby positively drive the feed 50 rolls when the platen is rotated, said pinions being splined on their shafts to permit adjustment of the rolls along the platen to accommodate cards of different widths, said card-guiding fingers also adjustable lengthwise of the rock shaft.

11. In a front-strike writing machine, the combination with a platen frame and a roller platen journaled thereon, of a rock shaft mounted in the platen frame and extending along the platen above the printing line, card-supporting and guiding fingers depending from said rock shaft at opposite sides of the printing point, card-feeding rolls supported in said fingers to bear against the platen at the printing line, a 70 spring to rock said shaft in a direction to cause the said rolls to bear against the platen, and a key for rocking said shaft in the reverse direction to throw the rolls off the platen. 80

12. In a front-strike writing machine, the combination with a platen frame and a roller platen journaled thereon, of a rock shaft mounted in the platen frame and extending along the platen above the printing line, card-supporting and guiding fingers depending from said rock shaft at opposite sides of the printing point, card-feeding rolls supported in said fingers to bear against the platen at the printing line, a 75 spring to rock said shaft in a direction to cause the said rolls to bear against the platen, a key for rocking said shaft in the reverse direction to throw the rolls off the platen, arms depending from said shaft adjacent the ends of the platen, roll shafts connected to said rolls and supported in said arms, pinions on said roll shafts, and gears secured to the platen to drive said pinions, and thereby positively drive said rolls at the 85 surface speed of the platen when the platen is rotated. 95

13. In a front-strike writing machine, the combination with a platen frame and a roller platen journaled thereon, of a rock shaft mounted in the platen frame and extending along the platen above the printing line, card-supporting and guiding fingers depending from said rock shaft at opposite sides of the printing point, card-feeding rolls supported in said fingers to bear against the platen at the printing line, a spring to rock said shaft in a direction to cause the said rolls to bear against the platen, a key for rocking said shaft in the 105 reverse direction to throw the rolls off the platen, arms depending from said shaft adjacent the ends of the platen, roll shafts connected to said rolls and supported in said arms, pinions on said roll shafts, and gears secured to the platen to drive said pinions, and thereby positively drive said rolls, said 110 fingers slidably mounted on the rock shaft, and the roll shafts having a sliding connection with their pinions, whereby the fingers, 115 rolls and roll shafts are adjustable lengthwise of the platen. 120

14. The combination with a roller platen, of card-supporting and feeding means comprising rolls arranged to bear against the 130

4

platen along the printing line at opposite sides of the printing point, an open unobstructed space being provided along the printing line between said rolls, means to 5 cause the rolls to bear with a yielding pressure against the platen, said rolls formed of hard material having a knurled or roughened surface to engage the cards, and prevent slipping, and means to positively 10 drive said rolls from the platen when the latter is rotated.

15. In a front-strike typewriting machine, the combination with a roller platen and frame, of card-holding and feeding means, comprising a rock frame including a rock 15 shaft extending lengthwise of the platen above the printing line and having its ends journaled in the platen frame, card-supporting and guiding fingers depending from said 20 shaft at opposite sides of the printing point,

and provided at their lower ends with pockets or stops for the lower edge of the card, feed rolls carried by said rock frame and extending along the printing line at opposite sides of the printing point, said 25 fingers and rolls arranged to provide an unobstructed space along the printing line, means to cause the rolls to bear against the front face of the card, and means to rock said rock frame and thereby space the rolls 30 and card-holding fingers from the platen to permit a card to be dropped into position between the platen and said rolls and to facilitate the removal of the card when the writing thereon has been completed.

BURNHAM C. STICKNEY.
